UNITED STATES PATENT OFFICE.

JAMES R. CARDWELL, OF CHICAGO, ILLINOIS, ASSIGNOR TO UNION DRAFT GEAR COMPANY, OF CHICAGO, ILLINOIS, A CORPORATION OF ILLINOIS.

DRAFT-GEAR.

1,070,774.

Specification of Letters Patent. Patented Aug. 19, 1913.

Continuation of application Serial No. 519,743, filed September 27, 1909. This application filed October 25, 1911. Serial No. 656,631.

To all whom it may concern:

Be it known that I, JAMES R. CARDWELL, a citizen of the United States, and resident of Chicago, county of Cook, and State of Illinois, have invented certain new and useful Improvements in Draft-Gear, of which the following is a specification, and which are illustrated in the accompanying drawings, forming a part thereof.

10 This application is a continuation of application Serial No. 519,743, filed September 27, 1909, which has been abandoned.

15 The invention relates to draft gear for cars and particularly to that type of draft gear in which friction is depended on in part to resist the stresses.

20 The objects of the invention are to secure a high degree of efficiency, and particularly to provide an initial spring resistance which acts in advance of the frictional resistance, whereby the frictional surfaces are called into action only to resist the heavier stresses to which the device is subjected.

25 The invention consists of a structure such as is hereinafter described, and is illustrated in the accompanying drawings, in which—

30 Figure 1 is a detail plan view of the frame of the car partly broken away, the draft gear being shown partly in plan and partly in plan-section and in a position of rest; Fig. 2 is a detail plan, partly in section, of some parts of the draft gear, drawn upon a larger scale; Fig. 3 is a detail section on the line 3—3 of Fig. 2; Fig. 4 is a perspective of 35 one of the levers used in the gear; Figs. 5 and 6 are views similar to Figs. 1 and 2, the gear being shown under compression due to buffing action; and Fig. 7 is a sectional view on the line 7—7 of Fig. 6.

40 The draft sills of a railway car are shown at 10, 11, and one of the end sills at 12. The draw bar 13 is of ordinary construction and is provided with the usual tail strap or loop 14 for encircling the followers 15, 16, which 45 operate with the stop lugs 17, 18, secured to the inner faces of the draft sills in the usual manner. Interposed between the planes of the followers 15, 16, are a series of wedge blocks, springs, abutments and toggle links, 50 through some or all of which the stresses are transmitted from the moving to the stationary follower and thence to the stop lugs.

The central wedge member 19 is of less

length than the normal distance between the followers, and its ends are tapered to form 55 wedging faces 20, 21, 22 and 23. The outer wedge members, two in number, shown at 24, 25, have their inner faces beveled toward their ends to form the wedging surfaces 26, 27, 28 and 29, the members 24, 25 60 being of substantially the same length as the central member 19. Interposed between the contiguous wedging faces of the member 19, and the members 24, 25, are a series of triangular wedging blocks 30, 31, 32 and 33, 65 the third face of each of these blocks bearing upon the inner face of a follower.

A bar 34 extends transversely through the draft sills 10, 11, and the wedging members 19, 24 and 25, and carries adjacent its ends 70 annular abutments 35, 36 held in place by nuts 37, 38, threaded upon the bar. A pair of sleeves 39, 40, are mounted upon the bar 34, their inner ends bearing respectively against the wedging members 24, 25, and 75 their outer ends carrying annular abutments 41, 42. Coiled expansion springs 43, 44, encircle the bar 34 and react respectively between the abutments 35, 41, and 36, 42. The members 24, 25, are free to slide 80 upon the bar 34 and the latter may have a loose fit in the member 19. The apertures, as 45, in the draft sills, within which the bar 34 is located, are of sufficient size to accommodate the sleeves 39, 40, and are elongated to permit these elements to move longitudinally of the sills. The followers 15, 16, have instanding flanges 46, 47, preferably continuous, which form a housing for the wedging elements, the depth of these flanges 90 being such as to permit the desired relative movement of the followers.

Toggle-links of the form shown in Fig. 4, are pivotally attached in pairs to the top and bottom sections of the flanges 46, 47, and 95 bear outwardly against the wedging members 24, 25; the levers connected to the flange of the follower 15 being shown at 48, 49, and those attached to the flange of the follower 16 being shown at 50, 51. 100 The wedge members 24, 25, are recessed, as shown at 55, 56, to loosely receive and provide bearings for the ends of the several toggle members, and the wedge links 19, 30, 31, 32 and 33 are recessed to permit the movement of these several members without in-

terfering with the action of the links. The wedge members 19, 24 and 25 are made of such length as to put the desired limit upon the travel of the followers.

- 5 The operation of the device is as follows: When at rest the several parts occupy the positions as shown in Figs. 1, 2 and 3, and under buffing stresses are forced toward and ultimately to the positions shown in Figs. 5, 10 6 and 7, the follower 15 being forced backwardly by the draw-bar 13, the links attached to its flange transmit the pressure to the wedge members 24, 25, and the combined action of all of the toggle-links force these 15 outer wedge members apart, compressing the springs 43, 44. The wedging blocks 30 and 31 move inwardly with the follower 15 but without material or any friction upon either the member 19 or the members 24, 25 during 20 the earlier part of the movement, for the reason that the spreading action of the toggle-mechanism during this part of the travel is sufficient to carry the outer wedge members away from their faces. The initial resistance is, therefore, offered by the springs. 25 The blocks 32, 33 are spread during the early part of the movement by the advance of the central wedge member 19, which is carried backwardly by the bar 34. As the toggle links approach the positions as illustrated in Figs. 5 and 6, their spreading action decreases and consequently the frictional engagement of the triangular blocks with the wedge members 19, 24, 25, is gradually augmented. 30 Under the influence of pulling stress the follower 16 moves forwardly, otherwise the action is the same as that already described.

I claim as my invention—

- 40 1. In a draft gear in combination, stop lugs, a pair of followers coöperating therewith, a transverse bar having abutments adjacent its ends, abutments sleeved upon the bar, springs re-acting between each set of 45 abutments, and links pivoted to each follower and transmitting pressure to the two sleeved abutments.

2. In a draft gear in combination, stop lugs, a pair of followers coöperating therewith, a transverse bar having abutments adjacent its ends, abutments sleeved upon the bar, one thereof facing each of the end abutments, springs reacting between each set of abutments, rigid links interposed between 55 each follower and both of the sleeved abutments, and friction devices interposed between the followers arranged to come into

frictional action after initial action of the links.

3. In a draft gear, in combination, stop 60 lugs, a pair of followers coöperating therewith, a transverse bar between the followers and having abutments adjacent its ends, a pair of abutments sleeved upon the bar, springs reacting between each of the sleeved 65 abutments and the adjacent end abutment, a pair of plates bearing outwardly upon the sleeved abutments, each plate having its inner face beveled toward its ends, a central wedging member, wedging blocks interposed 70 between the first-named plates and the central member and bearing against the followers, and rigid links interposed between the followers and the first-mentioned plates.

4. In a draft gear, in combination, stop 75 lugs, a pair of followers coöperating therewith, a transverse bar having abutments adjacent its ends, coiled springs sleeved upon the bar and bearing against the abutments, and links interposed between the followers and 80 the inner ends of the springs.

5. In a draft gear, in combination, stop lugs, followers, traveling abutments, springs seated on the abutments, links interposed between the followers and the springs and 85 constituting toggle mechanism with the followers, and a series of wedges interposed between the followers and arranged to be brought into action by the advance thereof after the initial compression of the springs 90 by the toggle action.

6. In a draft gear, in combination, stop lugs, followers, traveling abutments arranged transverse to the line of draft, abutments opposed to the first named abutments 95 and having their rearward faces beveled, springs interposed between the opposed abutments, links interposed between the followers and the second named abutments and acting with increasing power as the followers approach each other, and wedges interposed between the follower and the inclined faces of the second named abutments.

7. In a draft gear, in combination, stop lugs, a pair of followers coöperating therewith, a transverse bar having abutments adjacent its ends, coiled springs sleeved upon the bar and bearing against the abutments, and toggle-links interposed between the followers and the inner ends of the springs.
